DESIGN FOR A HAND TRUCK

Albert S. Johann, Milwaukee, Wis.

Application March 12, 1945, Serial No. 118,415

Term of patent 3½ years

(Cl. D14—3)

To all whom it may concern:

Be it known that I, Albert S. Johann, a citizen of the United States of America, residing at Milwaukee, in the county of Milwaukee and State of Wisconsin, have invented a new, original, and ornamental Design for a Hand Truck, of which the following is a specification, reference being had to the accompanying drawing, forming a part thereof.

In the drawing:

Fig. 1 is a perspective view of a hand truck showing my new design, the truck being disposed in approximately upright loading position;

Fig. 2 is a side elevational view of the hand truck, showing the same in horizontal position; and

Fig. 3 is an end elevational view of the hand truck, disposed in horizontal position as in Fig. 2 and viewed from the handle end thereof.

The characteristic features of my design are shown by means of full lines in the drawing.

I claim:

The ornamental design for a hand truck, substantially as shown and described.

ALBERT S. JOHANN.
